HYDROXY AROMATIC CARBOXYLATE-RESIN ADSORPTION COMPOSITION

Edwin L. Gustus, Chicago, Ill.

No Drawing. Application January 22, 1951;
Serial No. 207,225

8 Claims. (Cl. 167—65)

The invention relates to medicinal compositions and includes adsorption compounds of hydroxy mononuclear aromatic carboxylic acids, preferably mixed with compounds of succinic acid, particularly an adsorption compound thereof.

For many years the most satisfactory treatment agents for the mild and moderately severe cases of rheumatoid arthritis have been based on salicylates or on derivatives of salicylic acid. Sodium and calcium salicylate, acetyl-salicylic acid and its salts, salicyl-salicylate and salicylamid have been the more common forms in which the salicylic acid radical has been given.

A severe disadvantage of the use of treatment agents containing salicylic acid or its compounds has been the need for rather large dosages in order to obtain a satisfactory relief of symptoms. Such large dosages as are necessary to be effective frequently produce symptoms of salicylism or salicylate intoxication. Other undesired effects are also observed such as irritation of the stomach with consequent gastric distress. This is particularly disturbing to those suffering from gastro-duodenal ulcers or those with an ulcer diathesis and a previous history of ulcers.

More recently it was observed that when a salicylate is given to human subjects a portion of it is changed to gentisic acid among other products. This suggested that gentisic acid and gentisates might also show the therapeutic property exhibited by salicylates and led to a trial of the salts of gentisic acid in cases of rheumatoid arthritis.

As a result of these studies it was observed that gentisic acid and gentisates possessed the therapeutic activity toward rheumatoid arthritis which had been observed with salicylates. It was found, however, that gentisates had to be administered in rather large dosages, 10 to 26 grams daily being the usual dose. The latter dosage was given in severe rheumatic attacks at the start of therapy and after the attack was under control dosages of the order of 10 grams a day were recommended for maintenance. It was also noted that gentisic acid and gentisates given orally are rapidly absorbed and then rapidly eliminated from the blood stream by means of the kidneys. For this reason large total dosages were given, since the rapid absorption and elimination operated to decrease the effectiveness of the drug. A great many compounds and derivatives of gentisic acid were prepared by various investigators in the hope of finding some form in which gentisic acid could be administered which would not be so rapidly eliminated from the blood stream and hence would have a more prolonged action, requiring less total dosage of the drug.

An object of the invention is the provision of compositions containing a derivative of hydroxy mononuclear aromatic carboxylic acids, such as gentisic acid and salicylic acid, which have a prolonged action and require less total dosage of the drug.

A further object of this invention is the provision of new compounds and compositions for the treatment of rheumatoid arthritis at a cost considerably less than that of cortisone.

These and other objects are accomplished by combining an anti-arthritis hydroxy mononuclear aromatic carboxylic acid, including gentisic acid (2,5-dihydroxybenzoic acid), homogentisic acid (2,5-dihydroxyphenylacetic acid), and salicylic acid, with an acid adsorbing resin. Increased effectiveness is attained by mixing the adsorption compound with a succinate, and particularly with

2

an acid adsorbing resin having adsorbed thereon the anion of a succinic acid, i. e. the free acid or a monoester thereof. There appears to be a synergistic action between these two drugs, both useful in the treatment of rheumatoid arthritis, which makes the mixture more effective than either drug alone in comparable dosage. Of course, mixtures of an adsorption compound of resin and one hydroxy mononuclear aromatic carboxylic acid, and at least one other adsorption compound of resin and another hydroxy mononuclear aromatic carboxylic acid can be used alone or mixed with a succinate, or with other materials with or without the succinate. For example, a mixture of the adsorption compound of resin and gentisic acid and the adsorption compound of resin and salicylic acid can be used.

The term "hydroxy mononuclear aromatic carboxylic acids" as used herein, includes derivatives, in which there is substitution of the hydrogen of the hydroxy group or the hydroxy groups. For example, the term includes the acetyl derivatives, such as acetyl-salicylic acid. Another type of substitution is a lower alkyl, e. g., methyl and ethyl, ether of the hydroxy carboxylic acid. An example is the dimethyl ether of homogentisic acid, i. e., 2,5-dimethoxyphenylacetic acid, and the adsorption compound of it and the resin has been prepared.

The resin adsorption compounds of this invention are made by contacting an acid adsorbing resin (commonly called an anion exchange resin) with the desired acid. The preferred product is obtained by reacting a weak base acid adsorbing resin, such as a polyamine resin, having secondary or tertiary amino groups, with the organic carboxylic acid. This reaction may be represented as follows:

wherein RCOOH represents the hydroxy mononuclear aromatic carboxylic acid, and in the case of the succinate adsorption compound, to be used with the other adsorption compound, RCOOH represents succinic acid or a monoester of succinic acid.

Another form of the complex which is also effective, but in which the actual drug portion is more strongly bound, is obtained by reacting a strong base acid adsorbing resin, such as a quaternary ammonium anion exchange resin, with either the organic carboxylic acid or its salts. This reaction may be represented for the salt of the organic carboxylic acid as follows:

In the above equation A represents a resin nucleus, such as a polyamine-aldehyde or polyamine-ketone condensation product having amino or imino or tertiary amino groups represented by $-\text{NH}_2$, $-\text{NHR}$, $-\text{NR}'\text{R}''$ where R represents an aliphatic, alicyclic, aromatic or alkaryl residue and M represents a metal or ammonium ion.

Another form of the complex or adsorption compound results from the use of anion exchange resins which have been treated with a dilute solution of a soluble aluminum salt such as, for example, aluminum sulfate. Such products are included in the term "acid adsorbing resins."

The term "acid adsorbing resins" as used in this specification is to be understood as including what are commonly called anion exchange resins, thus covering resins containing no attached anion, those in free base form, and those which contain an anion of a weak acid. Acid adsorbing resins which can be utilized in the present invention are numerous and include those resins in which the acid adsorption or acid neutralization depends upon, for example, the presence in the resin of aromatic or aliphatic primary, secondary or tertiary amino groups, or the quaternary ammonium group structures. They

can be amine aldehyde or amine ketone condensation products. Such amine resins are referred to in this specification as polyamine acid adsorbing resins. One type of acid adsorbing resin which has given satisfactory results is sold by Rohm and Haas Co. under the trade name "XE-58." This is a weak base polyamine anion exchange resin. More particularly it is a polyethylene polyamine methylene substituted resin of diphenylool dimethyl methane and formaldehyde. The polyamine acid adsorbing resins disclosed in United States Patent 2,402,384 have also been highly satisfactory.

In addition to the particular type of polyamine aldehyde resin used in the examples cited here, other acid adsorbing resins can be used provided, of course, that they have sufficient adsorbing capacity for the carboxylic acids used in preparing the compositions of this invention and are physiologically innocuous. For example, a metaphenylen diamine-formaldehyde acid adsorbing resin could have been used although its adsorbing capacity is somewhat lower than that of the resin given in the examples. Still other acid adsorbing resins can be employed, such as acid adsorbing resins prepared from amines and polysaccharides, ethanolamine alkyd resins, alkylated aromatic diamines, and aromatic diamines both unmodified and modified by incorporating into the resin molecular structure during preparation alkyl groups to form quaternary ammonium bases. Also amine resins co-condensed with aliphatic polyamines or with polyimines can be used, or amine resins treated during preparation with cyanamide or with dicyandiamide, thus introducing the strongly basic guanidino group. Acid adsorbing resins prepared by reacting aliphatic polyamines with polyhalogen derivatives of hydrocarbons can be used, as well as acid adsorbing modified phenolic resins. In all cases, the resin should be physiologically innocuous or inert and should be sparingly soluble or insoluble in water and in dilute acids or bases.

The compositions of this invention can be used as such, which is in substantially moisture-free form, or they can be intermixed with other pharmaceutically compatible ingredients or excipients. For example, it may be desired to give it in capsules, pills, tablets, or as a powder, or even in syrups, elixirs, or emulsions. They can be intermixed with flavoring and coloring materials, clay, bentonite, antacids such as magnesium or aluminum oxide, aluminum phosphates, basic aluminum amino acetate and analogues and the like or bismuth suboxide, or bismuth or zirconium subcarbonates, emollients such as methyl cellulose, gastric mucin, carboxy methyl cellulose, sodium carboxy methyl cellulose, sulfated gluten and the like, or with naturally occurring gums and mucilages, gelatin, amino acids and their salts, peptones, peptides, or with any other ingredients cooperative therewith or not incompatible therewith.

The following examples illustrate the invention. Examples I, III and IV illustrate the complexes which are used in the compositions of the present invention, while Examples II and V illustrate the succinate complexes or adsorption compounds which are used with the complexes of hydroxy mononuclear aromatic carboxylic acids in a preferred embodiment. Examples VI through VIII illustrate the complexes or adsorption compounds which can be mixed with the complexes of hydroxy aromatic carboxylic acids of this invention in other embodiments thereof.

In all of these examples the acid adsorbing resin used was "XE-58" resin in finely powdered form and in free base form. The resin contained 2% moisture, removable by heating to 50° C. and maintaining at 50° C. until a constant weight was attained. In Examples I, II, VI, VII and VIII the resin was used without drying. In the other examples, the resin was heated at 50° C. to constant weight before use. In all examples, the weight of resin is stated on a dry basis. It will be evident from these examples that drying the resin, before use in the preparation of the adsorption compounds, is unnecessary. Of course, the same process can be used when making adsorption compounds using other acid adsorbing resins.

EXAMPLE I

Saturated complex of acid adsorbing resin and gentisic acid

264 grams of "XE-58" resin were placed in a glass vessel and 1000 ml. of distilled water were added. After stirring well, a slurry of thoroughly wetted resin powder

in water resulted. To this were added with stirring 317 grams of gentisic acid, C. P. anhydrous. This was added in portions, although the entire amount can be added at one time. The suspension was allowed to stand at room temperature for two to three days with occasional stirring. The suspended saturated complex of the polyamine acid adsorbing resin and gentisic acid was then filtered off by suction and the cake was washed three successive times with approximately its own volume of distilled water, sucking the wash liquor down well each time.

The damp cake was broken up and air dried at room temperature and was then dried in air to constant weight at 48-50° C. The resulting product weighed 554 grams and contained 53.1% gentisic acid and 46.9% resin. The filtrate and wash liquors were found to contain about 27 grams of gentisic acid which has been present as a slight excess. The dry powder was slightly more orange colored than the original resin. It was pulverized and sifted through an 80 mesh screen and it was then ready for use. The product kept well at room temperature and was sparingly soluble in water. Some degree of hydrolysis occurred when the material was shaken up with distilled water and an acid solution resulted containing gentisic acid in small amounts.

EXAMPLE II

Saturated complex of acid adsorbing resin and succinic acid

200 grams "XE-58" resin were added to 1000 ml. of distilled water in a glass vessel and stirred until a smooth, thoroughly wetted slurry resulted. 200 grams of C. P. succinic acid crystals were added with stirring over a four hour period. The mixture was allowed to stand at room temperature for three days with frequent stirring. The suspended saturated complex of polyamine resin and succinic acid was filtered off and washed by suction three times, using each time a volume of distilled water approximately equal to the volume of the moist cake of resin complex. The cake was broken up and dried in air at room temperature and then at 48-50° C. to constant weight. The dried product weighed 329 grams and contained 40.5% succinic acid and 59.5% resin. The mother liquor was found to contain 71 grams of unreacted succinic acid. This solution is suitable for inclusion in a subsequent preparation in place of a corresponding amount of water and of succinic acid. The product was powdered and sifted through an 80 mesh screen before use. On placing some of the practically insoluble product in water and shaking, the water became acid due to some hydrolytic cleavage of the saturated resin complex.

Following the preparation of the gentisic acid complex mentioned above it was put up into capsules and tried on patients with mild to moderate rheumatoid arthritis. It was found that very considerable and satisfactory relief was obtained when two or three capsules each containing 350 mg. of the saturated complex (52% gentisic acid) were taken at five intervals during the day. A great decrease in the swelling around the involved joints was observed in a short time and the amount of movement possible in the joint was considerably increased. The patient observed that the amount of urine voided was increased and this was compatible with the reduction of the swelling around the joints which was due to edema.

Since the total quantity of gentisic acid taken in one day, using the gentisic acid-resin complex, was of the order 1.75 grams to 2.8 grams, it was easily seen that this was far below the lowest dosage reported for sodium gentisate in effective dosage (5 grams per day) and very much less than the more customary dosages of this salt, namely, 15-26 grams per day used in severe cases.

A product was then made by mixing together the pulverized resin complex of gentisic acid with the similar product containing succinic acid, and this mixture was found to give excellent therapeutic results at still lower total dosages of gentisic acid. In this case the product was prepared by mixing 35 grams of a gentisic acid-resin complex containing 54.5% gentisic acid and 33.6 grams of succinic acid resin-complex containing 39.75% succinic acid. The mixture then contained 19.1 grams of gentisic acid and 13.38 grams of succinic acid on a total weight of the mixed resin complexes of 68.6 grams. The mixture contained, therefore, 27.9% gentisic acid and 22.8% succinic acid. It was put up in capsules each containing 343 mg. Each capsule, therefore, represented 95.8 mg. gentisic acid and 74.8 mg. of succinic acid. This preparation

was effective in a moderate case at dosages of six to ten capsules a day, representing a total dosage of 575 mg. to 958 mg. of gentisic acid per day. It is obvious that this preparation represented a great advance in the therapeutic approach to rheumatoid arthritis on a symptomatic basis, and it may be mentioned here that there is no other type of therapy than symptomatic treatment known for this disease at present.

In this embodiment using adsorption compounds of hydroxy mononuclear aromatic carboxylic acid, such as gentisic acid, and of succinic acid, it is preferred that the aromatic carboxylic anion content and the succinic acid anion content be approximately equal, although wide variation in the ratio can be made.

EXAMPLE III

Saturated complex of acid adsorbing resin and salicylic acid

25 grams of "XE-58" resin and 27 grams of salicylic acid were added to 800 ml. of distilled water, and the mixture was stirred at room temperature for four hours. The suspension was filtered on a suction funnel and the clear filtrate was strongly acid and contained salicylic acid. The resin salicylic acid adsorption complex, retained on the suction funnel, was freed from uncombined salicylic acid by thrice repeated gravity washing with 100 ml. portions of acetone, in which free salicylic acid is very soluble. The final portions of the third acetone wash were removed by suction and the resin-salicylic acid adsorption complex was dried in air at 50° C. It weighed 42.42 grams and contained 37.8% of salicylic acid and 62.2% resin.

EXAMPLE IV

Saturated complex of acid adsorbing resin and salicylic acid

280 grams of "XE-58" resin were added to 2000 ml. of distilled water in a five liter flask. The mixture was agitated until a smooth suspension resulted and the resin was thoroughly soaked. This required about an hour. 315 grams of powdered salicylic acid, C. P., were added and the mixture was agitated until a smooth mixture resulted. The flask and contents were allowed to stand at 40-45° C. for four to five days with frequent shaking. The contents of the flask were then collected on a suction funnel and the clear filtrate after warming to 40-45° C. was refiltered through the cake in the funnel. This process of warming the filtrate and refiltering it through the cake was repeated eight times and the final filtrate, which was slightly acid, was discarded.

The damp cake was freed from mother liquor as much as possible by pressure and suction. The cake was then given three washes using each time about one-half its volume of C. P. acetone. The acetone removed water and any free salicylic acid. The final acetone wash was sucked from the well pressed cake, as far as possible, and the cake was broken up as finely as possible and dried in air at room temperature and finally in air at 50° C. until constant in weight. The product weighed 576 grams and consisted of 280 grams of resin on which was adsorbed 296 grams of salicylic acid; thus, the product contained 51.6% salicylic acid and 48.4% resin.

A comparison of Examples III and IV shows that a greater amount of acid adsorption is obtained by saturation at a higher temperature.

Modifications to a gentisate-succinate-resin preparation for rheumatoid arthritis

In the case of the resin complex of succinic acid the product has a very acid reaction in the stomach, probably due to the fact that a large portion of the adsorbed succinic acid molecules are attached to the resin by only one carboxyl group. This leaves a carboxyl group free and available for ionization of hydrogen ions. Consequently, it is advisable to buffer the succinic acid-adsorption complex with an appropriate buffer, e. g., a phosphate buffer mixture in any final pharmaceutical product.

The composition containing the complex of the resin and succinic acid can be used as an enteric coated form so that the tablet or capsule would not open in the stomach but would open in the intestinal tract. A coating of salol is suitable therefor.

Another procedure is that of substituting for the resin-succinic acid adsorption complex, as described, a saturated complex of the resin with a monoester of succinic acid,

e. g., a monobenzyl ester of succinic acid. A resin complex of the monobenzyl succinate would yield on hydrolysis monobenzyl ester of succinic acid which is apparently as active as is succinic acid. Further hydrolysis in the alimentary tract gives benzyl alcohol and succinic acid or sodium succinate. Instead of the monobenzyl ester of succinic acid, a lower alkyl, such as ethyl, monoester of succinic acid can be used, preferably as the adsorption compounded with the acid adsorbing resin.

EXAMPLE V

Saturated complex of acid adsorbing resin and monobenzyl ester of succinic acid

15 50 grams of "XE-58" resin were stirred up with enough distilled water to make a thin slurry, and this was allowed to stand with occasional stirring for one hour. The well soaked resin powder was filtered off by suction and washed several times by suction with small amounts of distilled water, and the cake was sucked down well to remove most of the mechanically held water.

20 The damp resin cake was transferred quantitatively to a one liter beaker, washing in the last traces with a little distilled water. Fifty grams of monobenzyl ester of succinic acid were rubbed up in sufficient distilled water to

25 give a slurry free of lumps and as finely divided as possible, and this was then washed into the beaker containing the resin. Distilled water was then added until the beaker was about 60% full and the resin and monobenzyl ester of succinic acid were stirred to give a smooth suspension. The beaker and contents were placed in a warm area so that the temperature of the suspension reached 40-45° C. and was allowed to stand at this temperature with frequent stirring for forty-eight hours. The supernatant liquor should be acid to litmus paper but not to congo paper at this point.

30 The saturated resin complex was filtered off by suction and washed twice with a volume of distilled water approximately that of the cake. The cake was then washed three times with portions of isopropyl alcohol, each portion approximately one-half the volume of the cake and each wash being removed by suction before adding the following wash. Finally, the washed cake was dried in air at room temperature and then at 50° C. until constant in weight. The product weighed 95 grams and contained 50 grams of resin to which was adsorbed 45

35 grams of monobenzyl ester of succinic acid. It contained, therefore, 47.45% monobenzyl ester of succinic acid and 52.55% resin.

40 Also it should be kept in mind that a final pharmaceutical preparation for rheumatoid arthritis can contain, besides the complex of resin and hydroxy mononuclear aromatic carboxylic acid, such as gentisic acid, alone or with a succinate, preferably a complex of succinic acid, drugs like ascorbic acid, para-aminobenzoic acid and 45 nicotinic acid. These drugs could be added as such or as their complexes with resins. Since such complexes are new, the preparation of them will be described.

45 50 While it should be kept in mind that a final pharmaceutical preparation for rheumatoid arthritis can contain, besides the complex of resin and hydroxy mononuclear aromatic carboxylic acid, such as gentisic acid, alone or with a succinate, preferably a complex of succinic acid, drugs like ascorbic acid, para-aminobenzoic acid and 55 nicotinic acid. These drugs could be added as such or as their complexes with resins. Since such complexes are new, the preparation of them will be described.

50 55 EXAMPLE VI

Saturated complex of acid adsorbing resin and ascorbic acid

60 65 20 grams of "XE-58" resin were placed in a glass container with the 20 grams of ascorbic acid crystals. While stirring the powder, 300 ml. of distilled water were added. A smooth slurry resulted.

70 75 The suspension was allowed to stand for fourteen hours with frequent stirring. The saturated resin complex with ascorbic acid was then filtered off by suction and washed three times, using each time a volume of distilled water approximately equal to the volume of the resin-complex cake. The product was then dried in an atmosphere of nitrogen at room temperature at sub-atmospheric pressure to constant weight. The dried product weighed 38.4 grams and contained 48% adsorbed ascorbic acid and 52% resin.

80 85 EXAMPLE VII

Saturated complex of acid adsorbing resin and para-aminobenzoic acid

13 grams of para-aminobenzoic acid were dissolved in 125 ml. of methyl alcohol and then 125 ml. of distilled water at 50° C. were stirred in. The warm solution was decanted from any traces of manufacturing debris and 85 to the clear solution 10 grams of "XE-58" resin sus-

pended in 100 ml. of 50% by volume methyl alcohol were added with stirring. The suspension was allowed to stand for three days at room temperature with occasional stirring.

The saturated complex of "XE-58" resin and para-aminobenzoic acid was collected on a suction filter. The filtrate was quite acid, showing that an excess of para-aminobenzoic acid had been used. The filter cake was washed four times by gravity, using each time a volume of methyl alcohol equal to the volume of the cake. The cake was finally sucked down well and dried at room temperature in air, then to constant weight at 50° C. The product weighed 17.5 grams and contained 43% adsorbed para-aminobenzoic acid and 57% resin.

EXAMPLE VIII

Saturated complex of acid adsorbing resin and nicotinic acid

35 grams of "XE-58" resin powder were added with stirring to 1500 ml. of distilled water at 40° C., in which were dissolved 30 grams of nicotinic acid. The suspension was then allowed to stand at 40° C. for three hours with frequent stirring, and then for about twelve hours at room temperature with occasional stirring. The saturated resin-nicotinic acid complex was collected by suction on a Buchner funnel and was sucked free as possible of aqueous liquor. The filtrate was acid to litmus paper and contained nicotinic acid, assuring that an excess had been used.

The resin-nicotinic acid complex cake was washed three times, using each time a volume of distilled water approximately equal to that of the cake. The distilled water was warmed to 40° C. The wash water was removed from the cake as far as possible by suction and the cake was crumbled and dried in air, first at room temperature and finally to constant weight at 50° C. The final product weighed 53.94 grams and contained 36.5% nicotinic acid and 63.5% resin. The acid filtrate containing the excess nicotinic acid could be used to replace nicotinic acid and water in a subsequent preparation.

While the foregoing examples illustrate the preparation of adsorption compounds of hydroxy mononuclear aromatic carboxylic acid in which the acid adsorbing resin is saturated with such acids, the present invention is not limited to the use of resins saturated either at room temperature or at elevated temperature with these carboxylic acids. The same is true with regard to succinate adsorbed on an acid adsorbing resin when the latter is to be used with the adsorption compounds of hydroxy mononuclear aromatic carboxylic acids. Similarly, resin complexes of other materials such as used in Examples VI through VIII need not have the resin saturated with such materials. It is preferred, however, that the resin be saturated with the anion of hydroxy mononuclear aromatic carboxylic acid, succinate, or the other material, where the succinate or other material is used as the complex.

The adsorption compounds and compositions of this invention are also useful in the treatment of rheumatic fever. Particularly effective results in the treatment of

rheumatic fever are obtained by administering to the patient an acid adsorbing resin having adsorbed thereon 3-hydroxy-2-phenyl-cinchoninic acid.

While I have described certain preferred embodiments of my invention, many modifications thereof may be made without departing from the spirit of the invention; and I do not wish to be limited to the detailed examples, formulas and proportions of ingredients herein set forth, but desire to avail myself of all changes within the scope of the appended claims.

I claim:

1. A therapeutic composition suitable for the treatment of rheumatoid arthritis comprising a polyamine acid adsorbing resin having adsorbed thereon an anion of an anti-arthritis acid consisting of a benzene nucleus containing a maximum of two hydroxyl groups attached to the nucleus and a carboxyl-containing side chain having a maximum of two carbon atoms, at least one of the nuclear hydroxyl groups of said acid being adjacent to the carboxyl-containing side chain.
2. The composition of claim 1 wherein the acid is gentisic acid.
3. The composition of claim 1 wherein the acid is salicylic acid.
4. The composition of claim 1 wherein the acid is homogentisic acid.
5. A therapeutic composition suitable for the treatment of rheumatoid arthritis comprising a weak base polyamine acid adsorbing resin having adsorbed thereon an anion of an anti-arthritis acid consisting of a benzene nucleus containing a maximum of two hydroxyl groups attached to the nucleus and a carboxyl-containing side chain having a maximum of two carbon atoms, at least one of the nuclear hydroxyl groups of said acid being adjacent to the carboxyl-containing side chain.
6. The composition of claim 5 wherein the acid is gentisic acid.
7. The composition of claim 5 wherein the acid is salicylic acid.
8. The composition of claim 5 wherein the acid is homogentisic acid.
